UNITED STATES PATENT OFFICE.

ERNEST S. JEFFERIES, OF HAMILTON, ONTARIO, CANADA, ASSIGNOR OF ONE-THIRD
TO EBENEZER A. W. JEFFERIES, OF WORCESTER, MASSACHUSETTS.

MACHINE FOR HEATING METAL STOCK.

Application filed July 31, 1922. Serial No. 578,836.

To all whom it may concern:

Be it known that I, ERNEST S. JEFFERIES, citizen of the United States, residing at Hamilton, in the Province of Ontario, Dominion of Canada, have invented a new and useful Improvement in a Machine for Heating Metal Stock, of which the following, together with the accompanying drawings, is a specification.

10 My invention relates to a machine for heating metal stock, and has for its object to provide a machine that is adapted to automatically heat separate pieces of bar or rod stock by the passage of an electric current therethrough, for the performance of some 15 operation thereon, such as heading or drop-forging.

In so far as I am aware, the only machines of the above described type which have been 20 heretofore constructed, have been hand operated, and are adapted to heat only a single piece of stock at one time. Consequently when it has been desired to successively form or forge a large number of pieces of stock, 25 the production of finished pieces of material has been limited by the rapidity with which one or more operators may deliver the heated stock to another operator for the purpose of forming or forging the same.

30 According to the present invention, I propose to provide a machine for successively heating a number of pieces of stock and delivering the heated pieces at definite intervals for the performance of the forming 35 or forging operation thereon. My invention further contemplates the provision of a mechanism that is entirely automatic in its operation, so that it is only necessary for the operator to place the stock in the several 40 receiving hoppers of the machine, after which the heated pieces of material are discharged from the machine at predetermined intervals for the performance of some further operation thereon. The above, and other 45 advantageous features of my invention will hereinafter more fully appear, reference being had to the accompanying drawings in which,

Fig. 1 is a view in front elevation of a 50 machine embodying my invention.

Fig. 2 is a plan view of the machine shown in Fig. 1.

Fig. 3 is a transverse sectional view along

the line 3—3 of Fig. 1, looking in the direction of the arrows.

Fig. 4 is an enlarged view of one of the hoppers of the machine shown in Fig. 3.

Fig. 5 is a transverse sectional view along the line 5—5 of Fig. 4.

Fig. 6 is an enlarged fragmentary view, 60 showing a portion of the parts shown in Fig. 5.

Fig. 7 is a fragmentary plan view, showing a portion of the parts shown in Fig. 2, 65 upon an enlarged scale.

Fig. 8 is an end view of the parts shown in Fig. 7.

Fig. 9 is an end view of the master cam shaft removed from the machine.

Like reference characters refer to like parts in the different figures.

Referring first to Figs. 1 and 5, the machine comprises suitable containing means for the stock, such as one or more hoppers 1 which are generally rectangular in form and open at the top. The bottom plate 2 of each hopper 1 is inclined, and extends only partly across the hopper to an opening 3 extending the length of the hopper. A vertical magazine 4 is provided below each opening 3 by spaced parallel plates 5 and 6. The plate 6 is made adjustable with respect to the plate 5 in order to accommodate different diameters of stock, as will be herein-after described. An agitator bar 7, angular in cross section, extends longitudinally of the hopper 1, with its upper surface substantially flush with the bottom plate 2 at the edge of the opening 3. The bar 7 also terminates adjacent to the upper edge of the plate 6, enough clearance being allowed between the bar 7 and the plates 2 and 6 to permit the rotation of the bar, as best shown in the various positions thereof in Fig. 1.

As best shown in Fig. 4, each bar 7 is rotatably mounted in end plates 8 of the hopper 1 and is extended at one end beyond the hopper 1, where it is provided with a ratchet wheel 9. A pawl member 10 is adapted to engage the teeth of each ratchet wheel 9, and is pivotally mounted between arms 11 which are adapted to turn about the end of the bar 7. The upper ends of the arms 11 are pivotally connected by pins 12 to a rod 13 which extends all the way across the rear 105 ends of the hoppers 1. The rod 13 is con-

ected to an arm 14 mounted on a rocker shaft 15, and a second arm 16, mounted on the shaft 15, is connected by means of a rod 17 to a bell crank lever 18, which is adapted 5 to be oscillated on its pivot shaft 19 by means of a crank arm 20, as best shown in Fig. 3. The crank arm 20 is connected by means of a pin 21 to a gear 22, mounted on a shaft 23. The gear 22 is in mesh with a pinion 24 10 mounted on a shaft 25 which, as best shown in Fig. 2, is rotatably supported in bearings 26. A worm wheel 27 is mounted on the shaft 25 between the bearings 26, and is in mesh with a worm 28 carried at one end of 15 the shaft 29 of an electric motor 30. Rotation of the motor shaft 29 causes an oscillatory movement to be imparted to the bell crank lever 18 through the crank arm 20, which in turn causes a reciprocatory movement of the rod 13. This causes all of the 20 pawl arms 11 to be moved back and forth simultaneously to impart a step-by-step rotative movement to the agitator bars 7, in order to prevent the pieces of stock from 25 arching across the openings 3 as they move downward into the magazines 4, as will be hereinafter referred to.

As best shown in Figs. 4 and 5, pieces 31 20 of stock are adapted to move by gravity from the hoppers 1 into the magazines 4, and are adapted to be held in a pre-heating position at the bottom of the magazines 4 by means of spaced fingers 32 provided on the plates 5. A plurality of resilient fingers 33 project downwardly below the plate 6 and cooperate with the fingers 32 to hold a piece of stock 31 in the pre-heating position, from which it is adapted to be removed to the heating position by means of a transfer 40 mechanism which will now be described.

As best shown in Fig. 1, a plurality of transfer shafts 34 extend across the machine below each hopper 1, and a plurality of transfer arms 35 are mounted on each shaft 45 34 at points opposite to the spaces between the fingers 32. As best shown at section D—D in Fig. 1, each arm 35 is provided with a notch 36 which, when the arm 35 is in a substantially vertical position, permits 50 the lowermost piece 31 of stock in the magazine 4 to be supported by the fingers 32 and 33. As best shown at section B—B, Fig. 1, each shaft 34 has mounted thereon a lever 37 which has connected thereto a link 38 by means of a pin 39. The link 38 passes 55 through a guide 40 and is surrounded by a spring 41 between the lower end of the link 38 and the guide 40. The compression of the spring 41 tends to draw the link 38 60 downwardly and thereby hold a roller 42, mounted on the pin 39, in the path of movement of a step 43 carried on a vertically movable push rod 44, which is adapted to have imparted thereto an up and down 65 movement, as will be hereinafter described.

Upward movement of the rod 44 is adapted to turn the shaft 34 in a counter-clockwise direction and thereby move the arm 35 into the position shown at section D—D, in which position the lowermost piece 31 of stock is supported by the fingers 32 and 33. This position will hereinafter be referred to as the "pre-heating" position of the stock. When the rod 44 is moved downwardly the 70 spring 41 causes the roller 42 to follow the 75 step 43, turning the shaft 34 in a clockwise direction and moving the arm 35 into the position shown at section E—E. When this occurs, the notches 36 in the arms 35 engage the lowermost piece of stock and carry it 80 against a stop 45, the resilient fingers 33 permitting the withdrawal of the bar, and the upper surface 46 of the arm 35, supporting the piece of stock immediately above, and preventing its withdrawal. This position of 85 a piece of stock will be hereinafter referred to as the "heating" position, in which it is adapted to be clamped between a pair of electrodes, as will now be described.

As best shown in Figs. 2 and 3, a stationary electrode 47 is supported with its contact shoe 48 in alignment with the stop 45. The electrode 47 extends downwardly and is connected to one end of a section of a divided secondary winding 49 of a transformer, having a primary winding 50 and a core 51 supported by a frame 52. A movable electrode 53, provided with a contact shoe 54, is carried at the other end of the secondary winding 49, and, as best shown at 90 section C—C of Fig. 1, is slidably supported between bearing blocks 55, whereby the electrode 53 is adapted to move in a substantially horizontal plane. The secondary winding 49 being formed of separate laminations 56, 100 is somewhat resilient at its end, thereby permitting movement of the electrode 53. The movable electrode 53 is connected by means of a link 57 to one end of a rocker arm 58 mounted on a shaft 59. The other end of 105 the rocker arm 58 is acted upon by a spring 60, the pressure of which tends to turn the rocker arm 58 in a clockwise direction and force the movable electrode 53 in the direction of the stationary electrode 47. A roller 110 61 is mounted on the rocker arm 58, adjacent to the point of connection of the link 57 thereto, which roller is in the path of movement of a cam 62 carried at the upper end of the push rod 44, when the rod 44 is moved up 115 and down by a mechanism which will now be described.

As best shown in Figs. 1 and 3, each push rod 44 is pivotally connected at its lower end to a rocking lever 63 which is provided at 120 a point intermediate its ends with a roller 64. The roller 64 is held in engagement with the surface of a cam 65, mounted on the shaft 25 and provided with a projection 66, by the pressure of the spring 60 act- 125 130

ing through the roller 61 and the cam 62. The free end of the lever 63 is provided with a reduced portion 67 which is adapted to be received in a notch 68 provided on a 5 pivoted latch member 69. The latch member 69 is acted upon by a spring 70 which tends to hold it in engagement with the surface of a master cam 71, mounted on a shaft 72, and provided with a cam projection 73. 10 The cam 71 is so formed that the latch member 69 is held out of engagement with the lever 63 by the spring 70, at all times, except when the latch member 69 is engaged by the projection 73, whereupon the reduced portion 67 of the lever 63 is received 15 in the notch 68.

The shaft 72 is driven from the shaft 25 through the pinion 24 and the gear 22 on the shaft 23, and through a second pinion 20 74 and a gear 75 on the shafts 23 and 72 respectively, whereby the shaft 72 is driven at a speed which is much less than that of the shaft 25. The exact speed ratio between the shafts 25 and 72 is determined by the 25 number of hoppers 1 and sets of electrodes 47 and 53 which are employed in the machine. In other words, if there are ten hoppers and sets of electrodes, then the speed of the shaft 72 is only one-tenth of that of 30 the speed of the shaft 25. Bearing this relation in mind, for the purpose of illustration, although it is to be understood that a machine can be provided with any desired number of hoppers, it is obvious that the lever 63 will be engaged by the cam projection 66 ten times, while the latch 69 is being 35 engaged by the cam projection 73 once. As long as the latch 69 rides on the circular surface of the cam 71, the reduced end 67 of the lever 63 is not received in the notch 68 and consequently the lever 63 is moved about its left hand end as a fulcrum each time that it is engaged by the cam projection 66. So long as the right hand end of the lever 40 63 is free to move, it is obvious that no movement will be imparted to the rod 44. When, however, the cam projection 73 engages the latch 69, following nine movements of the lever 63, the latch 69 is so moved to cause 45 the reduced end portion 67 of the lever 63 to be received in the notch 68. When the lever 63 is again raised by the cam projection 66, its right hand end portion 67 will be held fast by the latch 69, so that the left 50 hand end of the lever 63 will be raised about the right hand end as a fulcrum against the pressure of the spring 41. An up and down movement is thereby imparted to the rod 44, which movement is adapted to actuate the 55 corresponding transfer arm 35 and movable electrode 53, as will now be described.

From the preceding description, it is believed to be clear that with a rod 44 in its lower position, the corresponding transfer 60 arm 35 will be maintained in the position

shown at section E—E, Fig. 1, by the spring 41, in other words, in position to hold a piece of stock against the stop 45. The corresponding movable electrode 53 will also be held in the position shown in Fig. 3 by the 70 spring 60, this position of the electrode corresponding to that occupied by the electrode when in engagement with the butt end of a piece of stock. If it be assumed however, 75 that the machine is just about to be operated with pieces of stock only in the hoppers, then it is apparent with the position of the parts shown, that the electrodes 47 and 53 will be separated and no current will be flowing through the secondary winding 49. 80

Upon operation of any one of the rods 44 by the corresponding lever 63, the upward movement of the rod will cause the cam 62 to immediately engage the roller 61 and turn the rocker arm 58 in a counter-clockwise direction to move the electrode 53 away from the electrode 47. Continued upward movement of the rod 44 will cause the step 43 to engage the roller 42 on the lever 37 and turn the shaft 34, together with its transfer arm 35, in a counter-clockwise direction into the position shown at D—D, 85 Fig. 1. It is apparent from the form of the cam projection 66, that the rod 44 will drop suddenly as soon as it reaches the limit of its upward movement, whereupon the spring 41, acting on the lever 37 through the link 38, will cause the transfer arm 35 to be moved from the position shown at D—D to the position shown at E—E. When this occurs, the lowermost piece of stock supported by the fingers 32, will be seated in the several notches 36, and the piece will be carried to the heating position where it is in contact with the stationary electrode 47 and the stop 45, the resilient fingers 33 permitting withdrawal of the lowermost piece, but holding the bar next above from dropping out of the hopper. As a piece is moved to its heating position as above described, the 90 spring 60, acting on the rocker arm 58, causes the movable electrode 53 to engage the butt end of the piece as soon as it reaches the heating position, so that electric current 95 immediately starts to flow through the piece between the electrodes 47 and 53. 100

The piece remains in the heating position with current flowing therethrough, until the corresponding rod 44 is again moved upwardly by the cam projection 66, following 105 a predetermined number of revolutions of the shaft 25. When the rod 44 again starts to move upwardly, the piece which has been heated is released by the simultaneous withdrawal of the movable electrode 53 and the 110 upward movement of the transfer arms 35, the slope of the notches 36 being such as to cause a piece to fall therefrom by gravity as soon as it is clear of the stop 45. The heated piece thereupon drops upon an inclined 115 120 125 130

apron 76 extending downwardly below the hoppers 1, down which it moves onto a conveyor chain 77 which carries it to one end of the machine, where it is discharged on any suitable receiving means, not shown, for the performance of any desired forming operation thereon while in its heated condition. A guide member 78 extends parallel to the chain 77 to retain the pieces of stock thereon.

10 As best shown in Fig. 2, the conveyor chain 77 is driven by a sprocket wheel 79 mounted on a shaft 80, which in turn is driven from a sprocket wheel 81. The sprocket wheel 81 is adapted to be driven from the motor shaft 29 by any suitable means, such as gearing 82 and a chain passing over the sprocket wheel 81.

15 As described above, it is apparent that each push rod 44 is adapted to be raised and lowered at intervals, the length of which is determined by the relation between the speed of the cam shafts 25 and 72 respectively, and it is obvious that the relation between the movements of different rods 44 25 will be directly dependent upon the movements of the corresponding latch members 69. In other words, if the latches controlling the movement of adjacent rods 44 are caused to be operated at different times, it 30 follows that the movement of the corresponding transfer arms 35 and the electrodes 53 will be separated by time intervals. To this end then, the several cams 71 are so arranged on the shaft 72 as to cause 35 the cam projection 73 to have different angular relations with respect to each other. The exact angular displacement of the cam projections 73 is determined by the number of hoppers 1, and if it be again assumed 40 that the hoppers are ten in number, then the cam projections 73 will be displaced from each other by one-tenth of a complete circle, or 36°. This relation is best illustrated in Fig. 9.

45 With the above described arrangement of cam projections 73 on the shaft 72, it is apparent that the several rods 44 will be operated at predetermined intervals, so that the pieces of stock will be successively 50 moved from a pre-heating position to a heating position, and then will be dropped on the apron 76, after being heated a predetermined length of time, the complete cycle of operations for each hopper 1 occurring 55 in orderly procession and with definite time intervals between the different movements. It follows then that so long as the hoppers 1 are supplied with stock, the individual pieces 31 will be removed therefrom, heated, 60 and then delivered to the conveyor chain 77 in regular order, the heated pieces being deposited upon the chain 77 with definite spacing therebetween, and being delivered for further operation thereon at definite time intervals. It is obvious from a consideration

of the entire mechanism that heated pieces of stock can be delivered by the machine at any desired rate, dependent upon the speed at which the motor 30 operates, and upon the number of pairs of contacts.

70 In addition to providing a mechanism for automatically heating pieces of stock, and delivering them in orderly procession, my invention further contemplates a machine which is substantially universal in its 75 application, in that it may handle different lengths and diameters of stock without making it necessary to appreciably change or adjust the mechanism. It is obvious that a bar of relatively large diameter 80 requires a greater amount of heating than a bar of relatively small diameter, and that ordinary variations in the amount of heat required may be obtained by varying the voltage across the primary winding 50, or 85 by varying the speed of the motor 30. In addition however, I have provided means whereby any one or all of the push rods 44 may be rendered inoperative for the purpose of preventing its corresponding 90 transfer arm 35 and movable electrode 53 from functioning, as will now be described.

95 As best shown in Figs. 2, 7 and 8, a rod 83 extends across the front of the machine above the electrodes, and is provided at intervals 100 thereon with pairs of fixed collars 84, between each pair of which is confined a coiled spring 85. A latch arm 86, pivotally mounted on a stud 87, is disposed substantially mid-way between each pair of collars 84 and 105 extends beneath the spring 85 in the direction of one of the push rods 44. Each arm 86 is provided with an upwardly extending fork portion 88 which is adapted to embrace the rod 83 with its arms 89 engaged with substantially the middle convolutions 110 of the spring 85. The end of each arm 86 is slabbed off, as indicated at 90, and the top portion of each push rod 44 is provided with a notch 91, best shown at C—C in Fig. 1, of 115 substantially the same form as the slabbed off portion 90 of the arm 86.

120 It is obvious from a consideration of the above described parts, that with the arms 86 extending substantially at right angles 115 to the rod 83, equal portions of the spring 85 on opposite sides of each arm 86, are adapted to exert substantially equal pressures on the arms. When however, the rod 83 is shifted to the right, as indicated in dot and dash lines in Fig. 7, all of the arms 86 125 will be held clear of the path of movement of the rods 44, owing to the fact that the left hand portions of the springs 85 will be somewhat more compressed than the right hand portions thereof. If however, the rod 83 should be shifted to the left, all of the arms 86 will be forced in the direction of the rods 44, as indicated in dotted lines in Fig. 7, by the pressure which is then ex- 130

ertered by the right hand portions of the springs 85. With the several arms 86 held in their left hand position, it is obvious that when any one of the rods 44 is moved upwardly to operate the transfer mechanism and the electrodes, the end portion 90 of the corresponding arm 86 will be forced into the notch 91 on the rod by the pressure of the spring 85. Consequently, the rod 44 will be prevented from moving downwardly to its normal position. As long as the rod 83 is maintained in its left hand position, the rods 44 will be successively locked against downward movement as they are lifted, one after another. As long as any rod 44 is locked in its upper position, the corresponding transfer arm 35 will remain in the position shown at D—D, Fig. 1, and the movable electrode 53 will be held away from the stationary electrode 47. Consequently, it will be impossible for a piece of stock to be heated by any pair of electrodes in which the operating rod 44 is locked in its upper position. Upon moving the rod 83 to the right, all of the rods 44 which may be locked in their upper position, will be released by the arms 86, and will thereupon be moved downwardly to their lower position, and the corresponding transfer and electrode mechanisms will operate as before.

From the foregoing, it is apparent that the heating of stock can be interrupted at any time and for any desired period by merely moving the rod 83 to the left. If, for instance, it is desired to heat only a few pieces of stock for test purposes, it is possible for the operator to cause one or two heated pieces to be delivered to the conveyor 77, after which the operation of the machine can be temporarily interrupted by moving the rod 83 to the left, thereby causing one or more of the rods 44 to be locked against movement. The rod 83 can be moved to the right when it is desired to resume normal operation of the machine. A still further advantage lies in the fact that when it is desired to stop the machine it is possible to discharge all of the heated pieces of stock therefrom, for it is obvious that when the rod 83 has been moved to the left, the machine will continue to operate until all of the rods 44 have been locked in their upper positions, in which case there are no more heated pieces left in the machine. In addition, any one or more of the rods 44 can be locked by moving the corresponding arms 86 into a locking position by hand, and holding it there until the rod 44 is moved upwardly. In this way the machine could be run with only a certain number of electrodes in operation, which of course, would decrease the rate at which heated pieces of stock are delivered to the conveyor chain.

As best shown in Fig. 4, the means for adapting the machine for handling pieces of

stock of different length, consists in providing each hopper 1 with an adjustable plate 92. The plate 92 in each hopper rests at its upper end on a pin 93, received in holes 94 provided in the side walls of the hopper. Each hopper 1 is provided with a number of pairs of such holes 94, so that the upper end of the plates 92 can be supported at different distances from the ends of the hoppers. Each plate 92 extends downwardly from the pin 93 at an angle, and terminates in a curved portion 95 which projects into the magazine 4 between the plates 5 and 6. A second positioning plate 96 is attached to the front wall 8 of the hopper 1 and also extends downwardly at an angle between the plates 5 and 6, the curved portion 95 and plate 96 converging and being spaced apart at their lower ends a distance substantially equal to the length of the pieces of stock which are to be handled in the hopper 1. When a number of pieces 31 of stock are thrown into the hopper, certain of the pieces roll along the bottom plate 2 and are directed between the plates 5 and 6 by the agitator 7. As the pieces enter the magazine 4 between the plates 5 and 6, they are gradually brought into alignment with each other by the curved portion 95 and the plate 96, so that the lowermost piece is properly positioned between the fingers 32 and 33 for operation upon by the transferer 35. In this way, the hopper 1 is adapted to handle pieces of stock of different lengths by merely shifting the plate 92, after moving the pin 93 into a different pair of holes 94, so that the distance between the lower edge of the curved portion 95 and the plate 96 will be substantially the same as the length of the stock to be handled.

In order to take care of pieces of stock of different diameter, the plate 6 is made adjustable with respect to the plate 5. As best shown in Fig. 5, the plate 6 is provided with blocks 97, and the plate 5 is provided with blocks 98 having a series of steps 99 thereon, the blocks being located beyond the ends of the hopper. The distance between the plates 5 and 6 can be adjusted by causing the blocks 97 to be seated in different pairs of steps 99, and the plates 5 and 6 are secured together with any desired adjustment therebetween, by means of bolts 100.

The resilient fingers 33 which coat with the fingers 32 in the plate 5, to hold the lowermost piece of stock in position, are provided with means for preventing the fingers 33 from bending inwardly and permitting the entrance of a heated bar which may have become stuck in the notches 36 of the transfer arm 35 when a piece of stock is removed from between the electrodes. This device consists of a stiff finger 101 coacting with each of the resilient fingers 33, the lower end of each finger 101 being received

in the bent over portion 102 at the end of the finger 33, and the other end of the finger 101 being loosely supported by means of a set screw 103 received in a slot 104. 5 The action of the finger 101 is such that when a piece of stock 31 is being removed from between the fingers 32 and 33, its upper end shifts to the base of the set screw 103, thereby permitting the fingers 33 to 10 yield. If, however, a piece which has become stuck to the transfer arms 35, should try to force its way between the fingers 32 and 33 on the backward movement of the transfer arm, the fingers 101 will shift so 15 that their upper ends engage the heads of the set screws 103, and thereby prevent the fingers 33 from yielding inwardly.

In order to keep the electrodes cool, the movable electrode 53 is provided with a pair 20 of parallel ducts 105 and 106, as best shown in Fig. 2. The duct 105 is connected to a supply pipe 107 and the duct 106 is connected to a discharge pipe 108 in the form of a coil which leads to a duct 109 provided 25 in the stationary electrode 47. The water is discharged from the electrode 47 to a pipe 110, so that a continuous stream of water is passing through the electrodes during the 30 operation of the machine.

35 From the foregoing, it is apparent that by my invention I have provided an improved machine for automatically heating pieces of stock by the passage of electric current therethrough, the machine being adapted to successively discharge separate pieces of stock at predetermined intervals. The machine is further adapted to handle different lengths and diameters of stock without requiring any material adjustments or rearrangement 40 of parts, thereby rendering it substantially universal in its operation. The machine is entirely automatic in its operation and once set in motion, all that is required of the operator is to keep the machine supplied with 45 pieces of stock.

I claim:

1. In a machine of the class described, containing means for pieces of stock, a plurality of pairs of electrical contacts, and 50 means for automatically moving pieces of stock in succession from said containing means to positions between different pairs of contacts.
2. In a machine of the class described, 55 containing means for pieces of stock, a plurality of sets of electrodes, and means for automatically moving pieces of stock in succession from said containing means to respective sets of electrodes.
3. In a machine of the class described, 60 containing means for pieces of stock, a plurality of sets of electrodes, means for automatically moving pieces of stock from said containing means to respective sets of electrodes in a predetermined sequence.

4. In a machine of the class described, containing means for pieces of stock, a plurality of pairs of contacts, means for automatically moving pieces of stock in succession from said containing means to different pairs of contacts, and further means for automatically releasing pieces of stock after they have been heated a predetermined amount. 70

5. In a machine of the class described, 75 containing means for pieces of stock, a plurality of pairs of contacts, means for automatically moving pieces of stock from said containing means to respective pairs of contacts, and further means for automatically releasing said pieces of stock in succession from said contacts after each piece has been heated a predetermined amount.

6. In a machine of the class described, containing means for pieces of stock, a plurality of sets of electrodes, and means for automatically moving pieces of stock from said containing means to respective sets of electrodes in succession and for discharging said pieces of stock after each piece has been 80 heated a predetermined amount. 90

7. In a machine of the class described, containing means for pieces of stock, a plurality of sets of electrodes, means for automatically moving pieces of stock in succession from said containing means to respective sets of electrodes, and further means for automatically removing pieces of stock in succession from said electrodes after each piece has been heated a predetermined amount. 100

8. In a machine of the class described, the combination with a magazine, a pair of electrodes and a conveyor mechanism, of means for moving pieces of stock from said magazine to a heating position between said electrodes, and for delivering a piece of stock to said conveyor after it has been heated a predetermined amount. 105

9. In a machine of the class described, 110 the combination with a plurality of magazines, each containing pieces of stock, a plurality of sets of electrodes and a conveying mechanism, of means for automatically moving pieces of stock from said magazines to 115 respective sets of electrodes, and for delivering them in succession in a heated condition to said conveying mechanism.

10. In a machine of the class described, 120 electrodes, means for supporting a piece of stock in a preheating position above said electrodes, and a pivotally mounted arm adapted by movement in one direction to move a piece of stock from its preheating position into heating position in engagement 125 with said electrodes, and by movement in the other direction to release the heated piece of stock.

11. In a machine of the class described, 130 relatively movable electrodes, means for

- supporting a piece of stock in a preheating the combination with a plurality of containing means for pieces of stock, a plurality of sets of relatively movable electrodes, a plurality of transferers and a plurality of operating members each adapted by its movement to first cause a transferer to move a piece of stock from said containing means to a position between said electrodes and then move one of said electrodes into engagement with said piece of stock following its arrival in the heating position.
12. In a machine of the class described, the combination with a magazine containing pieces of stock, relatively movable electrodes and a transferer, of an operating member adapted by its movement to first cause said transferer to move a piece of stock from said magazine to a position in engagement with one of said electrodes and then move the other of said electrodes into engagement with said piece of stock.
13. In a machine of the class described, the combination with a magazine containing pieces of stock, relatively movable electrodes and a transferer, of a reciprocating operating member adapted by its movement in one direction to cause said transferer to move a piece of stock from said magazine and support it in a position in engagement with said electrodes, and adapted by its movement in the other direction to move from said electrodes to said magazine and thereby release said piece of stock.
14. In a machine of the class described, the combination with a magazine containing pieces of stock, relatively movable electrodes and a transferer, of a reciprocating operating member adapted by its movement in one direction to move one of said electrodes into engagement with a piece of stock supported in contact with the other of said electrodes by said transferer.
15. In a machine of the class described, the combination with a magazine containing pieces of stock, relatively movable electrodes and a transferer, of a reciprocating operating member adapted by its movement in one direction to cause one of said electrodes to engage the end of a piece of stock supported between said electrodes by said transferer, and adapted by its movement in the other direction to move away from said piece of stock.
16. In a machine of the class described, the combination with a plurality of containing means for pieces of stock, a plurality of sets of relatively movable electrodes, a plurality of transferers and a plurality of operating members each adapted by its movement to first cause a transferer to move a piece of stock from said containing means to a position between said electrodes and then move one of said electrodes into engagement with said piece of stock, of means for automatically actuating said operating members in succession.
17. In a machine of the class described,
18. In a machine of the class described, the combination with a plurality of containing means for pieces of stock, a plurality of sets of relatively movable electrodes, a plurality of transferers and a plurality of operating members each adapted by its movement to first cause a transferer to move a piece of stock from said containing means to a position between said electrodes and then move one of said electrodes into engagement with said piece of stock, of a timing mechanism for automatically actuating said operating members in a predetermined succession.
19. In a machine of the class described, the combination with a plurality of containing means for pieces of stock, a plurality of sets of relatively movable electrodes, a plurality of transferers and a plurality of operating members each adapted by its movement to first cause a transferer to move a piece of stock from said containing means to a position between said electrodes and then move one of said electrodes into engagement with said piece of stock, of a timing mechanism adapted to intermittently actuate each of said operating members, the time interval between each actuation being determined upon the number of said operating members.
20. In a machine of the class described, the combination with a plurality of magazines each containing pieces of stock, a plurality of sets of relatively movable electrodes, a plurality of transferers and a plurality of operating members each adapted by its movement to first cause a transferer to move a piece of stock from said magazine to a position between said electrodes and then release said piece of stock, of a timing mechanism for automatically actuating said operating members in a predetermined sequence.
21. In a machine of the class described, the combination with a plurality of magazines each containing pieces of stock, a plurality of sets of relatively movable electrodes, a plurality of transferers and a plurality of operating members each adapted by its movement to first cause a transferer to move a piece of stock from said magazine to a position between said electrodes and then release said piece of stock after it has

- been heated, of a timing mechanism for automatically actuating said operating members at predetermined intervals.
22. In a machine of the class described, the combination with a plurality of magazines each containing pieces of stock, a plurality of sets of relatively movable electrodes, a plurality of transferers and a plurality of operating members each adapted by its movement to first cause a transferer to move a piece of stock from said magazine to a position between said electrodes and then release said piece of stock after it has been heated, of a timing mechanism for automatically actuating said operating members, at intervals, whereby each piece of stock is heated a predetermined amount.
23. In a machine of the class described, the combination with a plurality of magazines each containing pieces of stock, a plurality of sets of relatively movable electrodes, a plurality of transferers and a plurality of operating members each adapted by its movement to first cause a transferer to move a piece of stock from said magazine to a position between said electrodes and then release said piece of stock, of a timing mechanism for actuating said operating members in succession, and means for arresting the movement of each of said operating members following the release of a piece of stock by said transferer.
24. In a machine of the class described, the combination with a plurality of magazines each containing pieces of stock, a plurality of sets of relatively movable electrodes, a plurality of transferers and a plurality of operating members each adapted by its movement to first cause a transferer to move a piece of stock from said magazine to a position between said electrodes and then release said piece of stock, of means for automatically actuating said operating members in succession, and further means for successively locking each of said operating members against movement.
25. In a machine of the class described, the combination with a magazine containing pieces of stock, relatively movable electrodes, a transferer and a reciprocatory operating member adapted by its complete movement to cause said transferer to move a piece of stock from said magazine and support it in a position between said electrodes and then release said piece of stock, of means for arresting the movement of said operating member following its release of a piece of stock.
26. In a machine of the class described, the combination with a magazine containing pieces of stock, relatively movable electrodes, a transferer and a reciprocatory operating member adapted by its complete movement to cause said transferer to move a piece of stock from said magazine and support it in a position between said electrodes and then release said piece of stock, of means for arresting the movement of said operating member to prevent it moving a cold piece into position between said electrodes.
27. In a machine of the class described, means for supporting pieces of stock one above the other, a plurality of pairs of electrical contacts, a rotating element, and means automatically controlled by the rotation of said element for moving the lowermost pieces of stock in succession from said stock supporting means to positions in engagement with different pairs of contacts and for releasing the pieces of stock in succession after they have been heated a predetermined amount.
28. In a machine of the class described, means for supporting pieces of stock one above the other, a plurality of pairs of electrical contacts, a rotating element, and means governed by a predetermined degree of angular movement of said element for automatically moving, in regular succession, the lowermost pieces of stock from said supporting means to positions in engagement with different pairs of contacts and for automatically releasing, in the same succession, the pieces of stock after heating.
29. In a machine of the class described, a magazine for supporting pieces of stock, one above the other, a pair of spaced electrical contacts and automatically controlled means for moving the lowermost piece of stock broadside away from said magazine into a position in engagement with said contacts, for preventing the escape from the magazine of the piece of stock next above the piece removed and for releasing the said piece of stock from said contacts after it has been heated a predetermined amount.
30. In a machine of the class described, means for supporting pieces of stock one above the other, a transformer having an open secondary circuit constituted, in part, by a plurality of pairs of spaced contacts, and means for automatically causing the successive engagement of the lowermost pieces of stock with different pairs of contacts to cause the passage of an electric current through the stock by the completion of different portions of the secondary circuit.
31. In a machine of the class described, means for supporting pieces of stock one above the other, a transformer having an open secondary circuit constituted, in part, by a plurality of pairs of spaced contacts, means for automatically causing the successive engagement of the lowermost pieces of stock with different pairs of contacts to cause the passage of an electric current through the stock by the completion of different portions of the secondary circuit, and means for releasing the pieces of stock in

succession after each piece has been heated a predetermined amount.

32. In a machine of the class described, a magazine for supporting pieces of stock, one above the other, a transformer having an open secondary circuit including a pair of spaced contacts, means for automatically causing the broadside removal of the lower

most piece of stock from said magazine and its engagement with said pair of contacts 10 to cause the passage of an electric current therethrough by the completion of said secondary circuit, and means for releasing the piece of stock from said contacts after it has been heated a predetermined amount.

ERNEST S. JEFFERIES.

Certificate of Correction.

It is hereby certified that in Letters Patent No. 1,567,373, granted December 29, 1925, upon the application of Ernest S. Jefferies, of Hamilton, Ontario, Canada, for an improvement in "Machines for Heating Metal Stock," errors appear in the printed specification requiring correction as follows: Page 7, lines 53, 66, 80, and 94, claims 16, 17, 18, and 19, respectively, strike out the words "a plurality of"; and that the said Letters Patent should be read with these corrections therein that the same may conform to the record of the case in the Patent Office.

Signed and sealed this 2d day of March, A. D. 1926.

[SEAL.]

M. J. MOORE,
Acting Commissioner of Patents.
